10 Claims

ABSTRACT OF THE DISCLOSURE

One or more odorless zinc compounds, preferably zinc oxide, is mixed with bacterial protease in order to decrease the typical protease odor.

Proteolytic enzymes are well known and bacterial proteases are being used in washing compositions, especially for the purpose of laundering household fabrics and clothing. Enzymes of this type are especially useful for removing stains caused by blood, chocolate milk, gravy and other proteinaceous food residues. Enzyme compositions containing proteases can be used to make a presoaking bath for articles to be washed or they can be combined with detergents. Since many washing baths are alkaline, it is desirable that the proteolytic enzyme be sufficiently resistant to alkali so that its activity is not destroyed to the extent that the utility of the enzyme is nullified. Certain bacterial proteases have been developed which retain their activity in a pH range of about 5 to about 10.5 and are otherwise suitable for cleaning uses, either in a soaking or a prewashed product, or in a detergent product.

One of the problems encountered in the preparation of suitable bacterial proteases has been the objectionable odor of the proteases. This problem exists where the bacterial protease is used as such or in combination with bacterial amylase or in conjunction with other additives employed as stabilizing agents or for other purposes. The solution to this problem is complicated by the fact that enzymes, such as bacterial protease and bacterial amylase are sensitive to various types of chemicals and hence readily subject to loss of activity.

One of the objects of the present invention, therefore, is to provide new and improved bacterial protease compositions in which the characteristic bacterial protease odor is reduced or eliminated. Still another object of the invention is to provide new and improved compositions containing both bacterial protease and bacterial amylase characterized by the fact that the objectionable odor is reduced or eliminated.

Still a further object of the invention is to provide new and improved stabilized compositions containing bacterial protease and/or bacterial amylase which are adapted to be used for the preparation of a presoaking bath for articles to be washed or which can be combined with detergents.

Another object of the invention is to provide a new and improved process for reducing or eliminating the objectionable odor of a bacterial protease and/or a bacterial amylase by a method which does not destroy the protease and/or amylase activity. Other objects will appear herein-after.

In accordance with the present invention it has been found that the odor of bacterial proteases, either when used as such or when used in combination with bacterial amylases or stabilizing agents or sequestering agents or other substances, normally employed in the preparation of detergent compositions, can be reduced or eliminated without destroying the enzyme activity by incorporating with the bacterial protease or with a mixture of bacterial

2

protease in combination with one or more of such other materials a small amount of one or more odorless zinc compounds, preferably zinc oxide and/or zinc hydroxide.

The amount of zinc compound used for the purpose of the invention should be sufficient to reduce the characteristic odor of the bacterial protease. This amount is normally within the range of 0.1% to 3% by weight of a protease composition containing 15,000 to 1,500,000 PV units per gram (PVU/g.). The composition can also contain 0 to 1,500,000 DV units per gram (DVU/g.) of amylase. If the composition contains amylase, a preferred weight ratio of protease to amylase is 1:1 but this is subject to variation.

The compositions of the invention in which the odor has been inhibited by the addition of at least one odorless zinc compound can also contain stabilizing agents as, for example, calcium acetate monohydrate and inert ingredients or extenders, as, for example, neutral soluble inorganic salts, such as sodium sulfate and/or sodium chloride. In lieu of calcium acetate monohydrate, anhydrous calcium acetate can be used. The calcium acetate serves to stabilize bacterial protease against decomposition, especially in the presence of sequestering agents, such as tripolyphosphate, that are employed in many detergents. Neutral water soluble salts, such as sodium sulfate, are especially useful as carriers and for the purpose of permitting proper proportioning of the bacterial protease when the compositions containing the bacterial protease are used in wash waters as a presoak or when they are incorporated in detergent compositions.

The invention will be further illustrated but is not limited by the following examples in which the quantities are by weight unless otherwise indicated.

EXAMPLE I

A composition was prepared containing the following ingredients:

Ingredients	Total units $\times 10^6$		
	Grams	PV	DV
Bacterial protease.....	5.07	1.470	1.037
Bacterial amylase.....	33.00	2.068	2.942
Calcium acetate monohydrate.....	20.00	.....	.....
ZnO.....	0.25	.....	.....
Na ₂ SO ₄ to complete blend.....	41.68	.....	.....
Total.....	100.00	3.538	2.979

The above ingredients were added to a 400 milliliter jar in the order shown and blended for one hour. They were then ground to uniform mesh size and reblended for one hour. The resultant product was white, substantially odorless and contained 35,380 PV units per gram of bacterial protease and 29,790 DV units per gram of bacterial amylase.

EXAMPLE II

A composition was prepared by blending the following ingredients in the manner described in Example I:

Ingredients	Total units $\times 10^6$		
	Grams	PV	DV
Bacterial protease.....	10.14	2.941	0.074
Bacterial amylase.....	33.00	2.068	2.942
Calcium acetate monohydrate.....	20.00	.....	.....
ZnO.....	0.25	.....	.....
Na ₂ SO ₄ to complete blend.....	36.61	.....	.....
Total.....	100.00	5.009	3.016

A substantially odor-free product was obtained.

3
EXAMPLE III

A composition was prepared by blending the following ingredients in the manner described in Example I:

Ingredients	Total units $\times 10^6$		
	Grams	PV	DV
Bacterial protease	10.14	2.941	0.074
Bacterial amylase	16.50	1.034	1.471
Calcium acetate monohydrate	20.00		
ZnO	0.25		
Na ₂ SO ₄ to complete blend	53.11		
Total	100.00	3.975	1.545

The product was substantially free from odor.

EXAMPLE IV

2 parts of enzyme paste containing 490,000 PV units per gram of bacterial protease was dry blended with 5 parts of calcium acetate monohydrate. 3 mixtures prepared in this manner were blended, respectively, with 0.1 part zinc oxide, 0.05 part zinc oxide, and 0.025 part zinc oxide. Each mixture was then finally blended with 15 parts of tripolyphosphate. The odor of each composition was good. These compositions were dissolved in water to give a 0.25% solution having pH's of 9.4, 9.3 and 9.25, respectively which were clear. Each composition was also assayed and found to contain respectively, 43,920, 44,800 and 40,000 PV units per gram of bacterial protease.

EXAMPLE V

A composition was prepared by blending 10 parts of a wet cake of bacterial protease and bacterial amylase, 25 parts calcium acetate monohydrate, 0.25 part zinc oxide and 20.75 parts of sodium sulfate. This composition also was substantially odor-free. This composition contained 104,571 PV units per gram of bacterial protease and 6,333 DV units per gram of bacterial amylase.

The composition can be further diluted by adding sodium sulfate.

EXAMPLE VI

A composition was prepared by blending 10 parts of a wet cake of bacterial protease and bacterial amylase with 25 parts calcium acetate monohydrate, 0.25 part of zinc oxide and 20.75 parts of sodium tripolyphosphate. This product assayed 98,000 PV units per gram of bacterial protease and 6644 DV units per gram of bacterial amylase. It was substantially odorless.

EXAMPLE VII

The procedure was the same as in Example V except that the quantity of calcium acetate monohydrate was increased to 37.5 parts and the quantity of sodium sulfate was reduced to 8.25 parts. Again a substantially odorless product was obtained.

EXAMPLE VIII

The procedure was the same as in Example VI except that the quantity of calcium acetate monohydrate was increased to 37.5 parts and the quantity of sodium tripolyphosphate was decreased to 8.25 parts. Again the product was substantially odorless.

EXAMPLE IX

The products prepared as in Examples V, VI, VII and VIII were each dissolved in water at room temperature at concentrations of 0.25% by weight giving solutions having pH's of 7.4, 7.2, 7.5 and 7.4, respectively. After 24 hours, the percent PV retention was determined and found to be 86.5, 94.8, 83.2 and 91, respectively.

In the following examples the blending procedure was the same as in Example I.

4
EXAMPLE X

Ingredients	Total units $\times 10^6$

EXAMPLE LIV

A commercial dry solid enzyme product known as Alkalase which assayed 123,100 PV/gram was mixed in proportions of 10 parts of said product to 0.1 part of zinc oxide by blending the components and hand grinding the mixture to prepare a uniform blend. The addition of the zinc oxide gave a marked odor reduction without destroying the activity.

EXAMPLE LV

The procedure was the same as in Example LIV except that a commercial product called Maxatase was used instead of Alkalase. This product had a labeled potency of 300,000 Delft units/gram (equivalent to 103,000 PV/gram). The addition of the zinc oxide gave a marked odor reduction without destroying the activity.

EXAMPLE LVI

The procedure was the same as in Example LIV except that 2 parts of calcium acetate monohydrate was also added. Again a marked odor reduction was obtained. A similar result was obtained when anhydrous calcium chloride was used instead of the calcium acetate.

EXAMPLE LVII

The procedure of Example LVI was followed using Maxatase instead of Alkalase and in each case an essentially odorless product was obtained.

It was also found that odor inhibition was obtained by using 2 parts of calcium acetate monohydrate alone, or 2 parts of anhydrous calcium chloride alone, per 10 parts of Alkalase or per 10 parts of Maxatase.

In the following examples the blending procedure in preparing the products was similar to that in Example I, except for the kinds and proportions of the components.

EXAMPLE LVIII

Ingredients	Total units $\times 10^4$		
	Grams	PV	DV
Bacterial amylase (TX 8-80) ¹	62.18	1.803	6.000

Total	100.00	3.538	2.944

^{1,2} Same as above, Example XV.

It has also been found that calcium acetate monohydrate alone in a blend of 32.40 parts of bacterial protease (P115-30), 20 parts of calcium acetate monohydrate and 47.60 parts sodium sulfate inhibits odor. Similarly, 20 parts of anhydrous calcium chloride substituted for the 20 parts calcium acetate monohydrate in the same composition inhibits odor. In another composition containing 7.30 parts bacterial protease (P115-30), 32.40 parts bacterial amylase (A108) and 40.30 parts sodium sulfate, the addition of either 20 parts calcium acetate monohydrate or 20 parts anhydrous calcium chloride inhibited odor.

It will be understood that the compositions described in the examples can be standardized to various levels of PV and DV activity by adding neutral soluble salts, such as sodium sulfate and/or sodium chloride, or by adding additional amounts of calcium acetate monohydrate or by adding sodium tripolyphosphate or sodium sulfite or thiourea or a chelating agent.

Examples of chelating agents which can be used are the disodium salt of ethylene diamine tetraacetic acid, the tetrasodium salt of ethylene diamine tetraacetic acid, the sodium salts of N-(hydroxyethyl)ethylene diamine tetraacetic acid, the sodium salts of diethylene triamine pentaacetic acid, and the sodium salts of nitryltriacetic acid.

In general, good results are obtained by the use of standardized compositions containing 15,000 to 150,000 PV units per gram and 0 to 150,000 DV units per gram.

One half of one percent (.5%) by weight of the product of Example I when added to a standard laundry detergent will give excellent results in wash waters to which the detergent enzyme formulation is added at a concentration of 0.15% and fabrics are washed with such waters at standard conditions (wash cycle of 10 minutes at 120° F. (48.9° C.) and a rinse cycle of 5 minutes at 100° F. (37.7° C.), both at 100 agitator cycles per minute.

In a series of standard wash tests, 0.75% of the enzyme composition of Example XXVIII was mixed with a commercial detergent (Axion base) and used in washing test cloths cut into swatches 6" x 3". The concentration of detergent in the solution was 0.1%. The washing tests were conducted at a temperature of either 120° F. or 140° F. for 10 minutes followed by a rinse cycle of 5 minutes at 100° F. pH values of the wash solutions were determined at the end of the wash cycle. Reflectance was determined before and after washing using a Hunter D-25 color difference reflectometer. In one series of tests a standard soiled cloth (EMPA 112) was used and in another series of tests another type of standard soiled cloth (EMPA 116) was used. In a wash test at 120° F. using EMPA 116 cloth the pH at the end of the wash cycle was 8.75 and the difference in reflectance 39.7. In another wash test at 120° F. using EMPA 112 cloth, the pH at the end of the wash cycle was 8.7 and the difference in reflectance was 24.4. In a third test using a wash cycle of 140° F. with EMPA 112 cloth the pH at the end of the wash cycle was 8.85 and the difference in reflectance was 32.8. In another test which was identical with the last mentioned test except that one gram per liter of wash water of sodium tripolyphosphate was added with the detergent, the pH was 9.1 and the difference in reflectance was 34.5. In all cases the results with the compositions of the present invention were better than those obtained with a commercial enzyme and in the case where addi-

tional sodium tripolyphosphate was added the difference in reflectance was 34.5 against 31.5 for a commercial enzyme. All of these tests were conducted on Milwaukee, Wisconsin, city water having a hardness of 135 p.p.m. as calcium carbonate.

Typical laundry detergent, for example, will contain 10% non-ionic surfactant (e.g., Triton 101), 60% sodium tripolyphosphate, about 20% sodium sulfate, and minor amounts of other additives, such as carboxymethyl cellulose, optical brighteners, and the like.

The invention makes it possible to prepare compositions which will retain their activity over relatively long periods of time and which can be stored, handled and incorporated with detergents or used as a presoak product in a very simple manner.

The invention is especially valuable in providing a method for reducing or eliminating bacterial enzyme odors without destroying the enzyme activity. The compositions of the invention do not suffer, therefore, from one of the principal objections inherent in the use of bacterial enzymes, such as bacterial proteases and bacterial amylases.

The invention is hereby claimed as follows:

1. A dry solid composition comprising an enzyme having a characteristic odor from the group consisting of bacterial amylase, bacterial protease and both bacterial amylase and bacterial protease intimately blended with an odorless inorganic zinc compound in an amount sufficient to decrease said odor.

2. A composition as claimed in claim 1 in which the quantity of said compound is within the range of 0.1% to 3% by weight of said composition.

3. A composition as claimed in claim 1 in which the activity of said protease in said composition is within the range of 15,000 to 1,500,000 PV units per gram, and the quantity of said compound is within the range of 0.1% to 3% by weight of said composition.

4. A composition as claimed in claim 3 in which said compound is zinc oxide.

5. A composition as claimed in claim 1 which comprises both bacterial amylase and bacterial protease.

6. A composition as claimed in claim 1 which also comprises an odorless inorganic water soluble calcium compound.

7. A composition as claimed in claim 1 which also comprises a neutral water soluble inorganic salt.

8. A dry solid composition comprising 15,000 to 1,500,000 PV units per gram of bacterial protease, 0 to 1,500,000 DV units per gram of bacterial amylase, intimately blended with zinc oxide in sufficient amount to reduce the odor attributable to said bacterial protease and said bacterial amylase.

9. A composition as claimed in claim 8 in which the quantity of zinc oxide is within the range of 0.1% to 3% by weight of the composition.

10. A composition as claimed in claim 9 which also comprises sodium tripolyphosphate.
